[57] CLAIM

The ornamental design for intrusion detector unit, as shown and described.

DESCRIPTION

FIG. 1 is a left perspective view of an intrusion detector unit showing my new design;

FIG. 2 is a right perspective view thereof;

FIG. 3 is a top plan view thereof;

FIG. 4 is a bottom plan view thereof;

FIG. 5 is a left side elevational view thereof;

FIG. 6 is a front elevational view thereof;

FIG. 7 is a right side elevational view thereof;

FIG. 8 is a rear elevational view thereof.

FIG. 1

FIG. 3

FIG. 4

FIG. 5

FIG. 6

FIG. 2

FIG. 7

FIG. 8
